INKWELL

James D. Thompson, Eureka, Calif.

Application April 17, 1940, Serial No. 330,097

6 Claims. (Cl. 120—5)

This invention relates to an inkwell, and especially to an attachment whereby the removal or replacement of a pen will serve to open or close a cover on the well.

It is old to construct an inkwell having a main and a connected auxiliary reservoir for the reception of ink, and a cover rotatably mounted thereon, said cover having an extension for the auxiliary reservoir which causes opening or closing of said reservoir when the cover is rotated. The object of the present invention is generally to improve and simplify the construction and operation of a cover opening and closing mechanism for inkwells of the character described, and especially to provide means actuated by the weight of a pen whereby rotary movement is transmitted to the cover to swing the extended portion thereof out of register with the auxiliary reservoir when the pen is removed, and for swinging it to register or close the auxiliary reservoir when the pen is replaced.

The invention is shown by way of illustration in the accompanying drawing, in which

Fig. 1 is a side elevation of the inkwell and attached cover actuating mechanism;

Fig. 2 is a plan view thereof;

Fig. 3 is a plan view of the inkwell and the base supporting the same, said view showing the cover and actuating mechanism removed; and

Fig. 4 is a sectional view taken on line IV—IV of Fig. 2.

Referring to the drawing in detail, A indicates in general an inkwell which may be made of glass or any other suitable material. The particular shape of the well is more or less immaterial, but in this instance it is shown as substantially square in outline, as it has a front 2, a back portion 3, and a pair of side walls 5 and 4. Formed centrally thereof is a main ink reservoir 6 and communicating therewith is an auxiliary reservoir 7, through which the pen is dipped when the well is used. Extending around the upper surface of the main reservoir of the well, and up to the side walls 8 and 9 of the auxiliary reservoir is an upwardly extending flange which forms a seat for a cover 11. The cover is in turn provided with a downwardly extending annular flange 12 to hold the cover in place and to guide it during rotational movement, as will hereinafter be described. It will also be noted that the cover is provided with an extended portion 14 which normally assumes a position in register with the auxiliary well to function as a cover therefor.

The main feature of the present invention is to provide a simple attachment which serves as

a support for a pen, such as indicated at 15, and which also serves to impart sufficient rotational movement to the cover to swing the extended portion 14 thereof into and out of register with the auxiliary well when the pen is replaced or removed. The mechanism required is a base B and a plate generally indicated at C, which is pivoted to the side of the base as shown at 16. The inkwell proper, when placed on the base, is secured against movement by an annular flange 17, which extends around the front and back and one side of the base. Centrally of the base is formed a circular-shaped boss 18, and in the bottom of the well is a pocket 19 for its reception. The flange 17, boss 18, and pocket 19 secure the well in position on the base. The plate C is substantially rectangular in shape; one end of the plate has a holder 19 formed and secured thereto to receive the pen 15. The opposite side thereof carries a counter-weight 20, and this is adjustable by the provision of a set screw 21 which extends through an elongated slot 22 formed in the plate. In the upper and central portion of the plate is formed an opening 23, and extending therethrough is an arm 24 which is secured to the center top portion of the cover in a suitable manner, as indicated at 25.

In actual operation, when the pen is placed in the holder 19 the weight thus supplied will rock the plate C about its pivot 16 and, through the arm 24, will impart rotational movement to the cover 11, causing it to swing the extended portion 14 over the auxiliary well 7 to cover the same. Conversely, by removing the pen, the counter-weight 20 reverses the rocking movement, and the rotational movement then transmitted causes the extended cover portion to assume the dotted line position shown at 26. Stop pins 27 and 28, or similar devices, are secured to the base in the path of movement of the plate C, and thus limit movement of the plate in either direction.

The device as a whole is exceedingly simple and substantial in construction. The mere removal or replacement of the pen 15 automatically opens or closes the auxiliary portion of the well, and this is the only portion that is uncovered, as the main portion of the cover 11 at all times maintains the main reservoir of the well closed. Evaporation of ink, or entrance of dust, is thus reduced to a minimum.

The plate C may be held on its pivot 16 by a nut 16a, and by removal thereof the plate C may be removed; and when this is removed, the cover 11 may be removed from the well and the well in turn may be removed from the base B for

cleaning, inspection, or otherwise. Obviously arm 24 may be detachably secured to the cover, and when this provision is made the cover and ink-well may be removed without detachment of the 5 cover actuating mechanism.

While this and other features of my invention have been more or less specifically described for 10 purposes of illustration, I nevertheless wish it understood that various changes may be resorted to within the scope of the appended claims.

Having thus described my invention, what I 15 claim and desire to secure by Letters Patent is—

1. In an inkwell having a main and a connected ink reservoir formed therein and a main 20 cover for the main reservoir with a portion of the cover extending over the auxiliary reservoir said main portion of the cover having a circular portion and a central point about which it is adapted to rotate, a member pivoted at one side of the 25 well, a holder on said member to receive a pen, said holder imparting pivotal movement to said member when a pen is inserted or removed therefrom, and means actuated by said pivotal movement for imparting rotational movement to the main cover about its central point to open or close the auxiliary reservoir.

2. In an inkwell having a main and a connected ink reservoir formed therein and a main 30 cover for the main reservoir with a portion of the cover extending over the auxiliary reservoir said main portion of the cover having a circular portion and a central point about which it is adapted to rotate, a rocker member disposed adjacent the well and having a holder formed 35 thereon for the reception of a pen, said rocker rocking in one direction when the pen is removed and in an opposite direction when the pen is replaced, and means actuated by the rocking movement of the rocker for imparting rotational movement to the cover to close or uncover the auxiliary reservoir.

3. In an inkwell having a main and a connected ink reservoir formed therein and a main 40 cover for the main reservoir with a portion of the cover extending over the auxiliary reservoir said main portion of the cover having a circular portion and a central point about which it is adapted to rotate, an auxiliary rocker member disposed adjacent the well and having a holder formed 45 thereon for the reception of a pen, said rocker rocking in one direction when the pen is removed and in an opposite direction when the pen is replaced, means actuated by the rocking movement of the rocker for imparting rotational 50 movement to the cover about its central point to close or uncover the auxiliary reservoir, and means for limiting rocking movement of the rocker and rotational movement of the cover.

4. In an inkwell having a main and a connected ink reservoir formed therein and a main 55

cover for the main reservoir with a portion of the cover extending over the auxiliary reservoir said main portion of the cover having a circular portion and a central point about which it is adapted to rotate, an auxiliary rocker member 5 disposed adjacent the well and having a holder formed thereon for the reception of a pen, said rocker rocking in one direction when the pen is removed and in an opposite direction when the pen is replaced, and a radially disposed arm 10 secured to the central point of the cover and connected at one end with the rocker, said arm through means of the rocker transmitting rotational movement to the cover about its central point to close or uncover the auxiliary reservoir.

5. In an inkwell having a main and a connected ink reservoir formed therein and a main 15 cover for the main reservoir with a portion of the cover extending over the auxiliary reservoir said main portion of the cover having a circular portion and a central point about which it is adapted to rotate, an auxiliary rocker member disposed adjacent the well and having a holder formed thereon for the reception of a pen, said 20 rocker rocking in one direction when the pen is removed and in an opposite direction when the pen is replaced, a radially disposed arm secured to the central point of the cover and connected at one end with the rocker, said arm 25 through means of the rocker transmitting rotational movement to the cover about its central point to close or uncover the auxiliary reservoir, and means for limiting rocking movement of the 30 rocker and rotational movement of the cover. 35

6. In an inkwell having a main and an auxiliary reservoir formed therein for the reception of ink and a rotatable main cover covering the main reservoir and having an auxiliary portion extended to cover the auxiliary reservoir said main 40 portion of the cover having a circular portion and a central point about which it is adapted to rotate, a plate pivoted to one side and below the inkwell, said plate extending above the pivot and having an adjustable counter-weight at one 45 end and a pen receiver at the opposite end, said plate adapted to rock about its pivot in one direction when a pen is placed in the receiver and in an opposite direction when the pen is removed, a radially disposed arm secured to the central 50 point of the cover and having one end extending through an opening formed in the rocker plate whereby when the plate rocks rotary movement is transmitted to the cover about its central point to open or close the auxiliary reservoir, and means for limiting rocking movement of the 55 plate about its pivot and simultaneously rotational movement of the cover.
